UNITED STATES PATENT OFFICE.

JOHN P. FERRITEE, OF BOSTON, MASSACHUSETTS, AND EARLY E. STRADLEY, OF
WEST ORANGE, NEW JERSEY.

SYSTEM FOR OPERATING RELAYS.

Application filed November 13, 1925. Serial No. 68,867.

This invention relates to a system whereby a relay may be operated by means of signals recorded on a phonograph record.

One of the objects of this method is to teach telegraph sending and receiving by means of phonograph records. Another object is to record high speed telegraph signals on a phonograph record and then to reproduce the signals at slow speed for the purpose of reading them by sound or to operate a telegraph printer or other suitable device.

In order to operate sounders or to interrupt a tone for instruction in telegraph operating by means of a phonograph record, it was necessary to cause the signals reproduced from the record to operate a relay. This is accomplished by recording a series of indentations on the record for each dot or dash signal. For example: a dot may be represented by approximately twenty indentations and a dash by sixty. These indentations may be recorded on the record by using a buzzer or an alternating current generator of a suitable frequency, to throw the phonograph recorder diaphragm into vibration when a control key is closed. In reproducing these signals, when the record is played, the vibrations of the reproducer stylus of the phonograph, as it moves over these indentations, are caused to operate the relay in one of the following ways.

With the foregoing and other objects in view the invention consists in the combination and arrangement of parts hereinafter described, certain embodiments thereof being shown in the accompanying drawings, in which:

Fig. 1 is a diagrammatical showing of the relay attached to a phonograph record whose stylus is directly attached to a telephone;

Fig. 2 is a similar showing of the relay attached to a phonograph record having its own diaphragm;

Fig. 3 is a showing of that illustrated in Fig. 1 in connection with the remainder of the system.

Fig. 4 is a showing of that illustrated in Fig. 2 in connection with the remainder of the system.

Referring more particularly to the drawings, the stylus of the reproducer is either connected directly to a telephone transmitter diaphragm, as shown in Fig. 1, where A is the carbon cup of the transmitter, B is the

diaphragm, C is the stylus and D is the phonograph record, or to a diaphragm of its own, as shown in Figure 2, where A is the carbon cup of the transmitter, B is the transmitter diaphragm, C is the air column, D is the auxiliary diaphragm, E is the stylus and F is the phonograph record. In this latter case, the telephone transmitter is actuated through an air column. The telephone transmitter is next caused to modulate a current sent through it in the usual manner. In this way, there is a modulated current flowing through the transmitter every time the reproducing stylus of the phonograph passes over a signal on the record. The alternating current component, which is only present during a signal, is next rectified and caused to operate a relay. One method of doing this is shown in Figure 3, where A is the carbon cup of the transmitter, B is the diaphragm, C is the stylus, D is the phonograph record, E is a battery connected in series with A and the primary winding of induction coil F. The vacuum tube detector circuit is represented by G and the relay to be operated is represented by H.

A second method of operating the relay involves the use of a device mounted in place of the regular reproducer of the phonograph.

This device is shown in Figure 4.

In Figure 4, A is a small bar pivoted at one end and carrying a contact near the other end, B is a flat spring, rigidly fastened at one end, carrying a contact near the other end, facing the contact on A. Spring B is attached by a stiff wire C to the inertia bar D, which carries the reproducing stylus E. F is the phonograph record.

The action of this device is as follows: When the reproducing stylus passes over the series of indentations on the record forming a signal, the spring B is caused to vibrate. Due to the inertia of the bar A, the contact on it does not follow exactly the movements of the contact mounted on the spring B. These two contacts are connected in series with a battery and the coils of the relay to be operated. A milliammeter placed in this circuit will drop practically to zero every time the reproducing stylus passes over a signal on the record. The relay, therefore, may be made to reproduce the signal by using the back contacts to actuate a sounder.

or other device. The circuit is shown in Figure 4, where G and G¹ are batteries, H is a relay coil and J is the sounder.

Having thus described our invention, we 5 claim:

A system for operating a relay comprising a telephone transmitter circuit, a vibratory diaphragm, a relay, a phonograph record attached to said diaphragm, a reproducer, means for placing a series of indentations on said record to represent a signal, means for reproducing said signal by passing the stylus of said producer over said indentations so as to vibrate said diaphragm,

said diaphragm being adapted to modulate 15 current passing through said transmitter circuit so as to operate said relay after rectification of said current, said diaphragm also being adapted to partially open and close a circuit containing a battery and the 20 coils of a relay at a sufficiently high frequency to practically stop the flow of current through the relay coils and allow the armature to be released.

In testimony whereof we affix our signatures.

JOHN P. FERRITER.
EARLY E. STRADLEY.
